TORQUE RESISTING LOCKING LUG FOR
THE CENTER TUBE OF A SPOOL REEL OR
WARP BEAMRobert V. Olson, Attleboro, Mass., assignor to
Mossberg Pressed Steel Corporation, a corpora-
tion of Massachusetts

Application November 24, 1951, Serial No. 257,997

3 Claims. (Cl. 242—123)

1

This invention relates to a spool reel or warp beam of the type in which there is a metal barrel with metal heads at the ends and a metal center tube.

Quite frequently because of the strains to which a spool or reel is subjected, there is a torsion existing between the center tube and the head tending to relatively rotate these parts, and frequently because of this torsion there will be a breaking or cracking between the junction of the head and the center tube at their junction.

One of the objects of this invention is to provide an arrangement which will resist a torsional twisting of the head and the center tube.

Another object of the invention is to provide an arrangement which will lock the center tube with reference to the head as it is put in place.

Another object of the invention is to provide an arrangement so that there will be a strengthening of the center section of the head when this center tube is assembled with it.

With these and other objects in view, the invention consists of certain novel features of construction as will be more fully described and particularly pointed out in the appended claims.

In the accompanying drawings:

Figure 1 is a side elevation with a portion thereof in section, showing a spool or reel constructed in accordance with this invention;

Figure 2 is a section on lines 2—2 of Figure 1;
Figure 3 is a section on line 3—3 of Figure 1;

Figure 4 is a fragmentary elevation of a portion of the center tube of a spool or reel showing a modified form of lug which is used in this invention; and

Figure 5 is a section on line 5—5 of Figure 4.

In proceeding with this invention, I lift from the stock of the center tube of a spool or reel a lug with an edge in a single plane to abut the edge of an inturned flange about the center opening of the head, and I also provide a spur along this edge which has been hardened by working of the same and which may be driven into the edge of the head flange so as to lock the head with reference to the center tube against these two relatively turning about a center axis. This raised lug also serves to align the parts so that the flaring of the ends of the center tube will draw the center tube and heads into their desired aligned position.

2

With reference to the drawings 10 and 11 designate generally heads at the opposite ends of a barrel 12 of the spool or reel shown in Figure 1, the junction being formed as at 13 between the flange 14 of the inner portion of the head and the end of the barrel. The outer portion 15 of the head is provided with a central opening 16 about which there is an inwardly extending flange 17 which has its inner edge in a single plane at substantially right angles to the center axis of the barrel. The center tube 18 is of cylindrical form and extends through the openings 16 in the heads and has at a location spaced inwardly from its ends lugs 19 cut and deflected 15 radially outwardly from its stock at a point inwardly from its end 20. This stock which is cut and outwardly deflected has an edge 21 which is also located in a plane at substantially right angles to the axis so that it will abut the end 22 of the flange 17 and thus serve to locate this tube axially with reference to the head. Each of the lugs also is provided with a spur 23 which will be hardened by working of the tools to form it to such an extent that this spur may be driven 20 into the edge 22 of the flange 17 to a point where there is a good abutment between the edges of the flange and edges of the lugs which are in planes at right angles to the axis of the spool. The ends of the tube 20 are then bent over or flared outwardly as at 24 so as to lock the heads and tube in assembly.

By this arrangement relative turning of the head and tube are supported so that such torsion will not twist or break the joints between the head and the tube.

In some cases the lugs 19 have their opposite edges 25 and 26 flaring as shown in Figure 1, but in other cases the lug 30 as shown in Figure 4 may be arched (see Fig. 5) to provide a concave inner portion 31 and convex outer portion 32 rather than being cut and raised from the stock as shown in Figure 3, and in this case the opposite sides of the lugs 33 and 34 will converge toward each other in the opposite direction as 40 shown in Figure 4.

I claim:

1. A spool or reel comprising a barrel, heads at its opposite ends having central openings each with an inwardly extending flange about the 50 opening, said flange having a generally continu-

ous edge, a center tube extending through the barrel and through an opening in a head and outwardly flared to hold it in place, lugs spaced from the end of the tube and projecting radially outwardly from the stock of the center tube with edges extending along and in abutting engagement with the end of said flange and axially extending spurs on the edges of said lugs projecting into the edge of the flange beyond said line of abutment to prevent relative turning of the head and tube about its axis.

2. A spool or reel as in claim 1 wherein the lugs have their axially extending edges converging toward each other.

3. A spool or reel as in claim 1 wherein the flange and the spurs which extend into the flange are of metal.

ROBERT V. OLSON.
